(57) **CLAIM**

The ornamental design for a tile leveling device, as shown and described.

DESCRIPTION

FIG. 1 is a front perspective view a tile leveling device; FIG. 2 is a top plan view thereof; FIG. 3 is a front elevation view thereof, the left, right and rear sides of which are identical; and, FIG. 4 is a bottom plan view thereof.

The broken line showing is for the purpose of illustrating portions of the tile leveling device which forms no part of the claimed design.
